(57) **CLAIM**

The ornamental design of a balloon catheter, as shown and described.

DESCRIPTION

FIG. 1 is a perspective view of a balloon catheter showing my new design;

FIG. 2 is a top plan view thereof, the bottom plan being a mirror image;

FIG. 3 is a front elevation view thereof, the rear elevation view being a mirror image;

FIG. 4 is a right side elevation view thereof; and,

FIG. 5 is a left side elevation view thereof.

The claimed design is broken in two in FIGS. 2 and 3 to indicate truncation.

1 Claim, 2 Drawing Sheets

FIG. 3

FIG. 4

FIG. 5
